UNITED STATES PATENT OFFICE.

HENRY C. HUNT, OF NEWARK, NEW JERSEY, ASSIGNOR TO ALEXANDER MCKIRGAN, OF SAME PLACE.

TRUNK-LOCK.

SPECIFICATION forming part of Letters Patent No. 243,778, dated July 5, 1881.

Application filed September 11, 1880. (Model.)

To all whom it may concern:

Be it known that I, HENRY C. HUNT, of Newark, in the county of Essex and State of New Jersey, have invented a new and useful Improvement in Trunk-Locks, of which the following is a specification.

My invention relates to trunk-locks, to be applied to the outer surface of the trunk the same as trunk-catches are now applied; and it 10 consists in a plate having a central pin, on which is hung the bolt and lock spring, which spring, besides being employed to hold the bolt in position, performs also the office of being a key-hole shield.

15 Figure 1 is an inside plan. Fig. 2 is a central vertical section. Fig. 3 is a front view of the plate, and Fig. 4 is the bolt detached.

In my construction, A is the plate to be secured entirely on the outside of the trunk, and 20 is provided with the central pin, B, carrying the bolt C and spring D. Below the central pin the spring is provided with a locking-pin, E, on its inner side, made to catch into one of the two holes F in the lower end of the bolt 25 for holding it locked or unlocked when the bolt either engages the hasp or catch G, or is released from it; or the same or a similar locking device may, instead, be attached to the upper end of the spring and bolt. The spring, lying 30 on the face of the bolt and being riveted to the pin B, is made to have the upper end, A, bear upon the body of the bolt, to prevent it from swinging around except by the action of the key. The lower end of the spring is bent, as

seen in Fig. 2, so as to press flat against the 35 inside of the key-hole H as a shield, and to prevent dirt or dust from getting into the lock.

The lower end of the bolt has a notch or 40 ward, I, in which the flange f of the key g works in locking or unlocking. In doing either 40 the key is pressed into the key-hole and pushes back that end of the spring, and that raises the pin E out of the hole F in which it was resting; then the flange of the key will turn around between the spring and plate and engage the bolt in the ward I, and move it to the right or left, as is desired, to cause the upper end, having the hook K, to lock with the hook L in the hasp G, or unlock from it.

The lock, being entirely on the outside of the 50 trunk, saves all cutting into the wood or body of the trunk, and besides is attached at a large reduction of expense, the hasp also being attached to the outside of the cover.

I have in this order of construction a very 55 simple and cheap trunk-lock, and one not liable to get out of repair.

What I claim as my invention, and desire to secure by Letters Patent, is—

The combination of the oscillating bolt C 60 and spring D, substantially as described, and the spring having the lower end to extend below the end of the bolt and bent to form a key-hole guard, substantially as set forth.

HENRY C. HUNT.
